UNITED STATES PATENT OFFICE

ROBERT J. BARTHOLOMEW, OF GERMANTOWN, PENNSYLVANIA, ASSIGNOR TO FLETCHER WORKS, INCORPORATED, OF PHILADELPHIA, PENNSYLVANIA, A CORPORATION OF PENNSYLVANIA

THROWING MACHINE

Application filed October 9, 1929. Serial No. 398,331.

This invention relates to an improvement in throwing machines and is particularly directed to the stop motion mechanism of such machines.

5 In throwing machines as usually constructed faller wires are employed, these wires being provided with guide eyes for the thread being handled and so constructed that when the thread breaks the faller wire corresponding to the broken thread will fall by gravity about its pivot and set stop motion mechanism into operation to stop the machine.

These faller wires are so arranged, so far as their mounting is concerned and their position with respect to the thread being handled, as to be maintained almost at dead center when the machine is run so that the tension on the threads being handled will be reduced to a minimum. Due to the fact that the faller wires are maintained at substantially dead center when the machine is in operation, it is customary to employ a stop for the faller wires so that the faller wires will fall toward the stop motion mechanism rather than in the opposite direction.

It will be understood that this mechanism is very light in construction so as to function properly but by the same token the mechanism is easily rendered inoperative. In present practice the faller wires as well as the stops therefor are constructed of iron or steel and I have found that these members apparently become magnetized, perhaps due to certain operations performed during their manufacture, with the result that due to magnetic attraction between the faller wires and the stops the faller wire fails to drop upon rupture of a thread being handled thereby with the result of course that the stop motion does not operate.

It is an object of the present invention to provide in throwing machines a construction so far as the faller wires and stops therefor are concerned whereby this detrimental characteristic is overcome in a simple, effective and inexpensive manner.

In the drawings accompanying this application:

50 Fig. 1 shows a faller wire and stop of a

throwing machine in elevation together with a diagrammatic showing of the stop motion mechanism; and

Fig. 2 is a view similar to Fig. 1 in plan. Referring to the drawings in detail, 1 designates a bracket supporting stop motion mechanism which is designated 2; this stop motion mechanism is well-known and hence will not be described in detail herein.

55 Pivoted on an upstanding portion of the bracket 1 is a faller wire 3 pivoted at 4 and provided with a faller foot or stop motion foot 5, this foot, as is customary, being so disposed as to engage a member 2' constituting a part of the stop motion mechanism 2 whereby the stop motion mechanism will be set into operation.

60 At the upper end of the faller wire 3 is an eye 6 which, as is usual, is made of porcelain or some similar material. 7 designates a stop, which for purposes of illustration is shown as a stop wire, this stop lying behind the faller wire and extending parallel to the axis of movement of the faller wire.

65 Above the faller wire and the eye 6 there are spools designated 8 and 9 from which the threads 10 and 11 are taken.

70 In practice it will be understood that there are a plurality of faller wires 3 as shown in Fig. 2, and that each wire is provided with a guide eye 6.

75 The pivot 4 of the faller wire is so positioned with respect to the thread being wound, and the faller wire itself together with the eye 6 are so shaped that when the machine is in operation the faller wire will be maintained practically at dead center. This is for the purpose of reducing as far as possible the tension on the thread 10, for example, which maintains the faller wire in operative position, the faller wire, as above explained, upon the breaking of the thread passing through the eye thereof, falling to the right as viewed in Fig. 1 to bring the faller foot into operative position with respect to stop motion mechanism 2.

80 Due to the fact that very little tension can be imposed on the threads being handled in the machine, it is to be appreciated that the faller wire construction is extremely light.

and must be so arranged as to operate easily inasmuch as otherwise upon the breaking of a thread the faller wire will fail to move about its pivot 4 to set the stop motion into 5 operation. The stop 7 is provided for the purpose of preventing the faller wire moving to the left as viewed in Fig. 1 away from the stop motion mechanism instead of in the opposite direction.

10 As above pointed out the stop 7 and faller wires 3 are made of iron or steel, as standard practice, and possibly due to operations performed in the course of their manufacture, or for other reasons, become magnetized so that there is a magnetic attraction 15 between the faller wires and the stop which prevents the faller wires from functioning so far as pivoting to set the stop motion into operation is concerned. To 20 overcome this inherent characteristic I propose to make either the faller wire or the stop members, or both, of materials which are not magnetizable. These materials might include glass, wood, compositions of 25 various kinds and most non-ferrous metals except nickel or cobalt.

Good results can be obtained by covering either the faller wires or the stops with materials such as rubber, porcelain tubing, etc. 30 and where in the appended claims the statement is made that the faller wire or the stop member, or both, is constructed of non-magnetizable material this expression is intended to cover not only the making of the 35 faller wires or the stop members, or both, of materials such as glass, wood, etc. but to cover also a construction wherein these members are covered with soft rubber or porcelain tubing, etc. as above mentioned.

40 What I claim is:—

1. In throwing machines, a faller wire, a stop therefor of non-magnetizable material intermediate the ends of said wire and in contact therewith during the operation of 45 the machine.
2. In throwing machines, a faller wire, a stop therefor intermediate the ends thereof, said faller wire being constructed of non-magnetizable material.
- 50 3. In throwing machines, a faller wire, a stop for engaging said wire intermediate the ends thereof during the operation of the machine, said faller wire and stop being constructed of non-magnetizable material.
- 55 4. In throwing machines, a faller wire, a stop wire cooperating therewith to hold said faller wire in operative position, said stop wire being constructed of non-magnetizable material.
- 60 5. In throwing machines, the combination of a faller wire, a stop wire, cooperating therewith to hold the faller wire in operative position, said faller wire being constructed of non-magnetizable material.

6. In throwing machines, the combination of a stop wire, a faller wire adapted to be engaged by said stop wire intermediate its ends, said stop wire and faller wire being constructed of non-magnetizable material.

7. In throwing machines, the combination of a stop wire, a plurality of faller wires cooperating with said stop wire whereby the faller wires are held in operative position, the material of said stop and faller wires being such as to eliminate detrimental magnetic attraction between the faller wires and the stop wire.

This specification signed this 5th day of Oct., 1929.
